CLAIM

The ornamental design for a blade for converting a skateboard into an ice board, as shown and described.

DESCRIPTION

FIG. 1 is a front, top and side perspective view of the blade for converting a skateboard into an ice board embodying the design of the present invention;

FIG. 2 is a front end elevational view thereof, the rear end being a mirror image of the front shown in FIG. 2;

FIG. 3 is a side elevational view thereof;

FIG. 4 is an opposite side elevational view thereof;

FIG. 5 is a top plan view thereof; and,

FIG. 6 is a bottom plan view thereof.
